CLAIM

(52) U.S. Cl.

The ornamental design for a lid handle for cooking pans as shown and described.

USPC D7/393; D8/310

DESCRIPTION

(58) Field of Classification Search

1. Lid handle for cooking pans

USPC D7/393, 394, 395, 601, 602, 608, 619.1,

1.1 : Perspective

D7/619.2, 620-623, 624.1, 624.2, 625;

1.2 : Front

D8/300, 307, 310

1.3 : Back

CPC A45F 5/1583; A47G 2023/0275; A47G

1.4 : Right

23/02; A47G 23/0266; A47J 45/06; A47J

1.5 : Left

45/07; A47J 45/071; A47J 45/077; B60N

1.6 : Top

3/10; B60N 3/103; B60N 3/105

1.7: Bottom

See application file for complete search history.

The broken lines in the figures illustrate the portions of the lid handle for cooking pans that form no part of the claimed design.
